UNITED STATES PATENT OFFICE.

ROBERT C. WAGNER, JR., OF CHAMPAIGN, ILLINOIS.

DESIGN FOR A FRATERNITY BADGE OR EMBLEM.

41,761.

Specification for Design.

Patented Sept. 12, 1911.

Application filed February 13, 1911. Serial No. 608,477. Term of patent 7 years.

To all whom it may concern:

Be it known that I, ROBERT C. WAGNER, Jr., a citizen of the United States, residing at Champaign, in the county of Champaign and State of Illinois, have invented a new, original, and ornamental Design for a Fraternity Badge or Emblem, of which the following is a specification, reference being had to the accompanying drawings, forming part thereof.

The figure is an elevation of a fraternity badge or emblem, showing my new design.

I claim:

The ornamental design for a fraternity badge or emblem, as shown.

R. C. WAGNER, JR.

Witnesses:

W. F. Woods,
MANFORD SAVAGE.
